UNITED STATES PATENT OFFICE.

JAMES R. HASKELL, OF PASSAIC, NEW JERSEY, ASSIGNOR TO JULIA W. HASKELL, OF SAME PLACE.

MULTICHARGE-GUN.

SPECIFICATION forming part of Letters Patent No. 484,010, dated October 11, 1892.

Application filed March 24, 1890. Renewed June 15, 1891. Again renewed March 9, 1892. Serial No. 424,270. (No model.)

To all whom it may concern:

Be it known that I, JAMES R. HASKELL, a citizen of the United States, residing at Passaic, in the county of Passaic and State of New Jersey, have invented certain new and useful Improvements in Multicharge-Guns, of which the following is a description in such full, clear, and exact terms as will enable any one skilled in the art to which my invention applies to make and use the same, reference being had to the accompanying drawings, making part of this specification, and to the letters of reference marked thereon:

Having reference to said drawings, Figure 1 is a longitudinal section through the primary breech of my improved gun upon the lines of its axis. Fig. 2 is a longitudinal section through the first magazine supplemental charge-chamber and also upon the line of its axis. Fig. 3 is a transverse section and a rear view on the line a' a' . Fig. 4 is a transverse section and an end view of the breech of the magazine, taken on the line c' c' . Fig. 5 is a plan of a breech ring plate that closes each and all of the cartridge-chambers in the magazines. The figure shows this plate viewed from the rear on the line b' b' . Fig. 6 is an edge view of this same ring. Fig. 7 is an elevation of a short transverse section of the rear end of the magazine-breech. Fig. 8 is an external view of the magazine, a longitudinal section of which is shown by Fig. 2. Fig. 9 is a detail to be hereinafter more fully described. Fig. 10 is a longitudinal section through a succession of supplemental magazine-chambers, taken on the line of their axes, this figure showing, also, a longitudinal external view of one-half of each of said supplemental sections of the gun. The parts of this figure are upon an enlarged scale and are intended to show more distinctly the magazine-breech ring cap X in its different relations to the breech of the magazine. Fig. 11 is a detail, upon an enlarged scale, hereinafter more fully described. Fig. 12 is a longitudinal section of a modified form of the gun, taken upon the line of its axis, showing, also, an external view of a portion of the gun. Fig. 13 is a transverse section taken on the line a'' , showing, also, a rear breech view of the primary magazine-chamber of Fig. 12. Fig. 14

is a transverse section taken on the line b'' of Fig. 12. Fig. 15 is a transverse section taken on the line c'' of Fig. 12. Fig. 16 is a transverse section taken on the line d'' of Fig. 12.

My invention consists, broadly, of a multicharge-gun in which the supplemental charge-chamber or cartridge-chambers are made, when taken collectively, in the form of a magazine, each chamber of which concentrates upon and discharges into the bore of the gun successively behind the projectile in its progress through the bore after the explosive of the charge in the primary breech. The construction of such a gun will be understood from the following description of the accompanying drawings, the features of novelty being pointed out in the claims concluding this specification.

The drawings show some of the forms in which my invention may be advantageously applied. It will be understood, however, that my invention is not limited to the precise forms herein illustrated and described, as various modifications may be employed without departing from the spirit of my invention or the scope of the concluding claims.

The primary breech and charge-chamber of the gun are shown by Fig. 1. This drawing is made upon a slightly-enlarged scale and the plan of breech shown by it is old, it being the ordinary type of breech-loading breech now in common use, and which may be replaced by any other style or form of the breech-loading type adapted to combine with the supplemental charge-chambers. The muzzle A of this breech-section is fitted in the breech B of the magazine. (Shown by Figs. 2, 8, and 12 of the drawings.) The breech B should be snugly fitted upon the muzzle A of the primary breech, the two parts being united together by means of screw-threads cut into the respective parts. The second and third supplemental magazines (shown by Figs. 10 and 12) are united together and to the primary magazine (shown by Figs. 2 and 8) in the same manner, substantially, that the primary magazine is united to the primary breech or section of the gun. The principal part B of the supplemental magazine may be made of any suitable cast or forged metal,

and I prefer to make it in one solid piece, the main bore *e*, the magazine-chambers *c c*, and the concentrating-chamber *d* being cut out of the solid metal by suitable boring-tools. The 5 breech ends of the magazine-chambers *c* are made conical and are closed by conic sections *o*, fixed to the inside of the breech ring plate *s* by means of screws *P*. These conic sections or breech-cones *o* of the magazine-chambers are plainly shown on the inside surface 10 of the breech ring plate in Fig. 6 and by dotted lines in Fig. 5. The office of this breech ring plate is to fit against the breech end of each cartridge-chamber and close them 15 all with cone stoppers simultaneously. The operation of this breech ring plate is as follows: It is embraced, as will be seen, Figs. 2 and 10, between the breech of the magazine and the breech screw-cap *X*, which is made 20 to screw to and fro on the breech of the magazine. In the breech end of the magazine pins *t* are placed to fit in corresponding holes *v* in the inside face of the breech ring plate *s*, and in the edge of this ring plate *s* a 25 groove *Q* is cut, into which the pin *Q'* enters through the screw-cap *X*. Assume now that the breech ring plate *s* and the breech screw-cap *X* and the magazine-chamber *c* are in the position (with reference to each other) shown 30 in the drawings, Fig. 2, to bring these several parts in their relation to each other (shown by *Y*, Fig. 10) the screw-cap *X*, which carries with it, through the agency of the pin *Q'* in the groove *Q*, without turning it, the 35 ring plate *s* until it clears the pins *t* in the end of the magazine-breech. As soon as that happens the spring-pin *r* is forced into a hole *f*, made in the breech ring plate *s*, carrying the ring plate round with it until the hole *c''* in the ring plate comes opposite 40 the cartridge-chamber *c* and the hole *c''* in the screw-cap *X*, as shown by *Y*, Fig. 10. This brings the charging-holes *c''* in the screw-cap *X* and in the breech ring plate *s* opposite 45 each other and opposite the cartridge-chamber *c* ready for loading. The spring-pin *r* is driven forward at the proper time by means of a cam *u*, bolted to the section *A* of the gun, and is thrown back by the spring as the pin 50 passes the cam. The charging-holes *c''* in Figs. 3 and 5 are the same charging-holes *c''* in *Y*, Fig. 10. These holes, like the cartridge-chamber *c*, are diagonal to the bore of the gun, but are brought in their right relations with 55 each other and the cartridge-chambers by the construction and operation of the breech screw-cap *X* and its attachments in the manner already described. Now this screw-cap, when screwed up hard in its place against the 60 breech ring plate, will doubtless stick and be hard to start back and unscrew to open the cartridge-chambers for another charge. To meet this difficulty, I have bolted a bracket *m* to the periphery of the cap, against which 65 a starting-screw in a similar bracket *n*, bolted to the outside of the magazine-chamber, is made to act and by which the cap *X* is started

back from its bearings, and is then further unscrewed by a suitable wrench fitted upon pins *l*, set in the periphery of the cap. 70

By the modified form of gun shown by Figs. 12, 13, 14, 15, and 16 the magazine form of the supplemental charge-chamber is retained; but the breech of the several cartridge-chambers of the supplemental magazines are closed 75 by separate screw breech-pins in the same manner, substantially, that the main breech of the gun is stopped, the breech-pin holders being shown by *a*, Fig. 13 of the drawings. The cartridge-chambers of the supplemental 80 magazines *B* are shown by *c*, as in Fig. 2, the main bore of the gun being shown by *e*, into which all the cartridges of the magazines are made to discharge, either into one common chamber or through several partition-chambers made in the muzzle of each section composing the gun, as shown by *c*, Figs. 14 and 16. These figures show, also, a modified form of the muzzle ends of the several sections, the muzzle ends in this case being slotted, as at 90 *c*, Fig. 14, and continued across the space *d*, (shown in Figs. 2 and 10,) the lands of the rifling being continued on the solid sections or bridges between the opening *c c c*, forming the channel communicating between the supplemental cartridge-chamber and the main bore of the gun. 95

To insure a tight joint between the breech and muzzle ends of the several sections forming the gun, I make the joint in the form of a 100 conic section by beveling down the muzzle ends and making a corresponding form in the breech ends, so that when the two or more sections are screwed together the two parts of the joint lap past each other, the object being to cause the expansion of the muzzle ends, due to the explosion and heat of the charge, to tighten the joint and prevent the escape of gas. 105

In the foregoing specification I have described what I conceive to be a good practical method of making the gun and reducing the invention to practice; but I have not endeavored to specify all the modifications which may be employed, the object of the specification being to instruct persons skilled in the art to practice my invention in the forms which I at present prefer and to enable them to understand its nature, and I desire it to be distinctly understood that the forms mentioned 115 by me of a few modifications are in no wise intended to exclude others not referred to, but which are within the spirit and scope of my invention. 120

Many of the details and combinations illustrated and above described are not essential 125 to my several improvements broadly considered. All of this will be indicated in the following claims, as the omission of an element or the omission of reference to the particular 130 features of elements mentioned are intended to be formal declarations of the fact that the omitted elements or features are not essential to the invention therein covered.

Having thus described my improvement, I claim as new and desire to secure by Letters Patent as follows:

1. In combination with a breech-section A, 5 one or more separable supplemental cartridge-sections, each section consisting of a magazine of separate cartridge-chambers arranged around and concentrating their fire into the bore of the gun.
- 10 2. In a multicharge-gun consisting of one or more supplemental charge-chambers composed of a magazine of two or more separate cartridge or loading chambers, a suitable breech piece or plate operating in combination with a screw-cap and simultaneously closing the breech of each and all of the cartridge or loading chambers.
- 15 3. In a multicharge-gun composed of one or more supplemental charge-chambers consisting of a magazine having a series of separate charge or cartridge chambers distributed around the bore of the gun and discharging into the same and a breech-cap X, in combination with a breech ring plate having pins or 20 stops operating to open and close simultane-

ously the breech of each and all of the charge-chambers.

4. In a multicharge-gun consisting of two or more separate magazine-sections, the bridges or supporting-sections formed between the 30 opening c at the end of the muzzle of each section by which a continuity of the bearing is maintained between the several sections to carry the projectile from section to section and in case the gun be rifled to contain the 35 lands of the rifling, substantially as described.

5. In a multicharge-gun consisting of two or more separate sections joined together to form the gun, a beveled or underlapping joint between the muzzle and breech of the several 40 sections, by which the expansion of the muzzle end, due to the explosion and heat of the charge, has the effect of tightening the joint between the two sections, substantially as described.

JAMES R. HASKELL.
